CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

INSULATOR.

Application filed March 15, 1922. Serial No. 543,908.

My invention relates to insulators and particularly to insulators of the link type.

One object of my invention is to provide an insulator, of the above indicated character, that shall so resolve longitudinal load forces into lateral components as to materially increase the mechanical strength thereof.

Another object of my invention is to provide an insulator of the link type that shall have increased surface resistance and decreased weight for a given difference of potential between the terminals thereof.

Another object of my invention is to provide an insulator of the link type that shall be so constructed as a solid of revolution as to readily adapt it to any one of a wide variety of circuit voltages by the simple expedient of varying its length.

Another object of my invention is to provide a link-type insulator of such shape as to facilitate its being constructed of porcelain or other refractory material and that shall so comprise balanced masses or properly proportional parts as to ensure against the occurrence of defects during its manufacture.

Another object of my invention is to provide an insulator of the link type in which the terminal or linked connector members shall be so doubly linked as to strengthen, and to more widely distribute stresses in, the insulating member.

In insulators of the link type, it has heretofore been usual to provide an insulating body member having interlinked re-entrant openings of substantially U-shape for the reception of terminal members of similar shape. Such insulators have been successfully employed in low-voltage service, in which the insulating body has been of small mass and of simple block construction. However, in high-voltage service where insulators of the link type are provided with petticoats, difficulties arise in the manufacture of the porcelain bodies which entail much care and precision in the proportioning of the parts. In fact, unless the quality and proportions of the porcelain mass are very exact and the shaping, firing and glazing thereof performed with great care, defects

which render the insulator useless are very likely to occur. These difficulties have been caused by the peculiar shape of the insulator in which a relatively thick central mass has been surrounded by a relatively thin petticoat portion.

The above mentioned features have naturally limited the size of link insulators and reduced the scope of service for which they are adapted. To adapt them to voltages of different ratings has usually entailed changes in the whole mass of insulating material. That is, they have been made larger or smaller, in substantially all dimensions, in accordance with the voltages which they were adapted to withstand. This feature occasioned the use of many different molds.

Further, by reason of the shapes of the terminal members, which are usually cables or rods interlinking each other at right angles, the main load forces are nearly all concentrated in the longitudinal planes of the intersecting loops.

In practicing my invention, I provide an insulating member, of refractory or other insulating material, that is a simple solid of revolution, symmetrical in all of its parts and in which the masses are so related as to reduce the likelihood of defects during manufacture. Substantially straight openings, of easy formation, are provided for the reception of the terminal members which are so interlinked in substantially square-knot formation, and so adapted to resolve the longitudinal load forces into lateral components, as to greatly increase the mechanical strength of the insulator. Further, by reason of its simple solid-of-revolution form, relatively deep annular grooves permit the formation of relatively large petticoats of any desired number, to thereby increase the surface resistance, and reduce the weight, of the insulator for a given voltage.

Figure 1, of the accompanying drawings, is a side view of an insulator and connecting members embodying my invention.

Fig. 2 is a view similar to Fig. 1, taken at right angles thereto, and

Figs. 3, 4 and 5 are views, similar to Fig. 1, but on a smaller scale, of insulators embodying modified forms of my invention.

As shown in Figs. 1 and 2, an insulating member 1, preferably of porcelain, is formed as a simple solid of revolution that is provided with a cylindrical body portion 2 and laterally extending discoidal petticoat or projecting portions 3 having perimetral grooves 4 therebetween.

At each end of the body portion 2, a pair of openings 5, the entrances of which register longitudinally opposite the entrances to the corresponding openings at the opposite end of the insulator, are sloped, in parallel relation from the entrances thereof and through the central body portion 2, to positions intercepting the farthestmost groove 4. These openings extend beneath the inner surface of the groove 4 that is nearest to the end at which the openings enter.

An insulator of the above described construction permits terminal or connector members 6, preferably of flexible or pliable metal construction, to be threaded through the openings 5, and around the body portion 2, substantially in the form of a square or reef knot having closed-end or loop portions 7 at right angles to the remainder of the connectors and doubly interlinked with each other.

The construction provides substantially double the direct compression area between the connector loops, which area is angularly rotated to the compression area in a usual link insulator to thus resolve the longitudinal load forces in the terminal members 6 into a lateral component, as indicated by arrows 8 in Fig. 1. By reason of the relation of the sloped openings 5 to the entrances thereof, the longitudinal load forces are further resolved into lateral components at the ends of the insulator, as indicated by arrows 9 in Fig. 1.

The forces being thus subdivided or distributed, permit the insulator to be of smaller volume and, therefore, more easily fired.

The general arrangement of parts provides an insulator of easy manufacture and of great strength, that is of increased surface resistance and of reduced weight for a given voltage between its ends.

As shown in Fig. 4, in which similar parts are designated by similar reference numerals, a modified form of my invention comprises an insulator similar to that of the above-described form, with the exception of the number of the petticoats 3 and the grouping thereof relative to the terminal members 6. This form of insulator illustrates the manner of adapting the same for voltages of widely different values by merely making it longer or shorter. Thus, a relatively long body member, of uniform lateral dimensions, may be cut or divided into insulators of any desired length to greatly facilitate the construction of insulators of widely different voltage-resisting values by

a simple molding, turning or other manufacturing operation.

As shown in Figs. 3 and 5, the laterally projecting portions 3 may be variously modified as to shape and dimensions, the form shown in Fig. 3 having the end portions 3 narrower but thicker, or otherwise shaped, to provide sufficient surface resistance, and the form shown in Fig. 5 having an elongated laterally-reduced intermediate portion 3.

While I have shown and described particular forms of my invention, various changes in the construction, shape and relation of parts may be effected therein without departing from the spirit and scope thereof, as set forth in the appended claims.

I claim as my invention:

1. In an insulator, the combination with an insulating structure comprising a plurality of laterally projecting portions and a reduced portion between said projecting portions, of a terminal connector for one end of the insulator comprising a portion embracing a portion of said reduced portion and longitudinally extending portions projecting from said embracing portion through openings in the insulator to said end. 85

2. In an insulator, the combination with an insulating structure having longitudinally spaced perimetral grooves and openings extending from each end of the structure to one of said grooves, of a terminal structure for each end of the insulator comprising a portion embracing a portion of said insulating structure in one of said grooves and portions projecting from said embracing portion through said openings to the same end of the insulator. 95

3. An insulator comprising a body member having a plurality of longitudinally spaced laterally projecting portions and openings extending from each end of the member to a space between said laterally projecting portions closer to the other end of the member than the space to which the openings from the other end extend. 105

4. In an insulator, the combination with an insulating member comprising a plurality of laterally projecting portions and reduced portions between said projecting portions, of a terminal connector for each end of the insulator comprising a looped member disposed in openings in said insulating member and extending partially around one of said reduced portions. 115

5. In an insulator, the combination with an insulating member having longitudinally spaced perimetral grooves and openings extending from each end of the member to one of said grooves, of a terminal member at each end of the insulator comprising an elongated member extending continuously from its end of the insulator through one of said openings, around one of the grooves and out 125 130

through the other opening at the same end of the insulator.

6. An insulator of the link type comprising an elongated body member having a plurality of longitudinally spaced laterally projecting portions and openings extending from the ends of the member to the spaces

between the laterally projecting portions thereof.

In testimony whereof, I have hereunto ¹⁰ subscribed my name this 10th day of March, 1922.

CHRISTIAN AALBORG.
